[57] **CLAIM**

The ornamental design for a chocolate representing a personal computer, as shown and described.

DESCRIPTION

FIG. 1 is a front elevational view of the chocolate representing a personal computer.

FIG. 2 is a top plane view thereof.

FIG. 3 is a side elevational view from the left of FIG. 1. FIG. 4 is a side elevational view from the right of FIG. 1.

FIG. 5 is a rear elevational view thereof.

FIG. 6 is a bottom plane view thereof.

FIG. 7 is a front perspective view thereof.

FIG. 8 is a sectional view taken along line 8—8 of FIG. 1.

FIG. 9 is a sectional view taken along line 9—9 of FIG. 1.

FIG. 10 is an enlarged view of the numerical read-out number.

FIG. 11 is an enlarged fragmentary view of the keyboard.

FIG. 12 is an enlarged fragmentary cross-section taken on line 12—12 of FIG. 9; and

FIG. 13 is an enlarged fragmentary cross-section taken on line 13—13 of FIG. 9.

FIGS. 10—13 are shown separately for clarity of illustration.
